UNITED STATES PATENT OFFICE

LE ROI EARLE HUTCHINGS, OF BUFFALO, NEW YORK, ASSIGNOR, BY MESNE ASSIGNMENTS, TO REMINGTON RAND INC., OF NEW YORK, N. Y., A CORPORATION OF DELAWARE

INDEX RECORD AND SIGNAL

Application filed October 14, 1926. Serial No. 141,612.

This invention relates to indexes and signals and has reference more particularly to index signals which are adapted to be attached to the edges of record cards or members.

5 An object of this invention is to provide an index signal adapted to be attached to the edge of the record card, said signal being further adapted to provide a maximum number of signals or indications with the 10 simplest and cheapest possible construction of signal.

Another object of this invention is to provide a signal of the class described in which one face of the signal is of one color and 15 the opposite face of a contrasting color, so that the two different colors on the same signal will give twice as many possible indications as if the signal is of the same color on both surfaces.

20 A further object of the invention is to provide a signal having a plurality of struck-out tongues radiating from a common center, each of said tongues preferably having an aperture or other differentiating characteristic so that the number of indications 25 possible with a single signal is considerably increased.

A still further object of the invention is to provide a signal which is especially adapted 30 to be removably attached to the edge of reference or record cards such as cards articulated to form a series; also to improve index signals in other respects hereinafter specified and claimed.

35 Reference is to be had to the accompanying drawings forming a part of this specification, in which,

Fig. 1 is a plan view of one surface of my improved index signal.

40 Fig. 2 is a plan view similar to Fig. 1 of the opposite face of the signal.

Fig. 3 is an edge view of a signal.

Fig. 4 is a fragmentary elevation of a series 45 of articulated cards to which my improved signals are applied.

Fig. 5 is a sectional view through a signal on line 5-5 of Fig. 4.

Fig. 6 is a plan view of one of a large number of types of record cards to which my improved signal may be applied,

Fig. 7 is an edge view of a signal of metal or other material coated with enamel, paint, etc.

Referring to the drawings by numerals, 10 indicates the improved signal which may be constructed of any suitable material, such as 55 metal, celluloid, cardboard and the like. This material may be transparent or opaque, and said signal material may be composite in nature, such as metal with colored enamel on each side, a plurality of pieces of celluloid 60 or other material cemented together, or paper cemented to celluloid, or other material, or the signal material may be all of the same material and not composite in character.

One of the salient features is that if desired 65 one surface of the index material may be of one color and the opposite surface of the material of a contrasting color. In Fig. 1, for example, one surface has been shown white, while in Fig. 2, the opposite surface has been 70 shown red, but any other colors may be used if desired. This feature makes it possible for the signal to give twice as many indications of the condition of accounts, reference data, etc., as if the material were of the same color 75 on both surfaces. However, if so desired, the signal may be of the same color on both surfaces, and still be highly efficient as to 80 number of indications due to further mechanical improvements to be hereinafter described.

The signal material is preferably formed 85 into the desired shape by means of dies or punches so as to provide a plurality of struck-out tongues 11 which may be slipped over the edge of a record card as shown in Figs. 4 and 5 so that the record card is confined between the tongue 11 and the body 12 of the signal material. The improved index signal may have one of these tongues, or there may 90 be a plurality of tongues, and they may be further so constructed as to lie in radiating positions or other desired positions with respect to the center 13 of the signal. In the example shown in Figs. 1 and 2, four of these 95 tongues have been shown as radiating from the common center 13, and these tongues thus lie at angles of ninety degrees one to the other.

In order to further differentiate the tongues and provide a greater number of pos- 100

sible indications or symbols for a given signal, different tongues may be provided with differently shaped apertures such as a circle 14 in tongue 15, a triangle 16 in tongue 17 5 and a square 18 in tongue 19. The tongue 11 has been shown plain without an aperture. Thus as an example of the utility of this novel signal, in using the same for accounts receivable, if the four tongues 11, 15, 17 and 19 indicate different classes of credit rating, white 10 surfaces exposed on a tongue would indicate first statement mailed to a customer, and a red surface exposed would indicate second statement mailed to the customer. In this 15 way the condition of a particular account could be seen at a glance simply by the indication given by the desired tongue of the signal.

The signal may be constructed of any suitable 20 material, but in the preferred form it is constructed of two pieces of transparent celluloid, opaque cardboard or other suitable material of different colors sealed together as shown in Fig. 3. If desired one layer of the 25 composite signal material may be of opaque material such as paper, while the opposite surface may be of transparent celluloid or the material may be of a single material such as metal, with different colored paints or 30 enamels on the opposite faces as shown in Fig. 7. Regardless of the material or construction used it is desirable, but not essential, for one surface of the signal to be of one color and the opposite surface to be of another 35 color.

While my improved signal may be applied to the edge of any type of record or reference card, it is especially adapted to be applied to the edge of a record card such as shown in 40 Fig. 6, which is adapted to be articulated or connected to a similar card by means of tongues 20 which engage in suitable apertures 21 formed in the body of said card 22. These apertures 21 may take the form of 45 diagonal slots, and are so spaced that one edge of each of said cards is in overlapping visible relation to equivalent edges of other cards in the series, and the signals are especially adapted to be applied to said exposed or visible edges of the record cards. The tongues 20 on the end card of the series 50 may be inserted in suitable apertures or slots 23 in a panel 24, of cardboard, metal, or other suitable material so that the series 55 of cards 22 is supported from the tongues on said end card of the series. It will be seen that the signals may be instantly attached to or detached from record cards, and transferred from one card to another card, or ap- 60 plied to a given card so that another tongue is exposed, giving a different indication or signal. In the preferred form shown in Figs. 1 and 2, eight different indications or signals 65 may be given by the index signal simply by attaching the index signal to the edge of the

reference card 22 with the desired colored tongue exposed to view.

I would state in conclusion that while the illustrated examples constitute a practical embodiment of my invention, I do not limit myself precisely to the features herein illustrated and described, since manifestly the same can be considerably varied without departing from the spirit of the invention as defined in the appended claims. 75

I claim:

1. In an index signal, a signal member composed of composite material consisting of two differently colored substances attached together, said signal being provided with means for attaching said index signal to the edge of a record card said differently colored substances being adapted to indicate characteristics of record matter on said card. 80

2. In an index signal, a signal member, a plurality of tongues struck from said signal member, each of said tongues being adapted to detachably engage the edge of a record card, and each of said tongues having different indications or signals formed thereon. 85

3. In an index signal, a signal member, and a plurality of tongues struck from said signal member and radiating in position from the center of said signal member, each of said tongues having a differentiating characteristic 95 and being adapted to be detachably secured to a record card.

4. In an index signal, a signal member having a plurality of tongues struck from the body of said member, said tongues being 100 adapted to separately and detachably engage the edge of a record card, one of said tongues having a distinctively shaped aperture therein so as to provide a differentiating signal for said tongue.

5. In an index signal, a signal member, a plurality of tongues struck from the body of said signal member, some of said tongues having a distinctively shaped apertures formed therein, one surface of said signal member 110 being of one color and the opposite surfaces being of another color.

6. In an index signal, a signal member, and a plurality of tongues formed on said signal member, one of said tongues having an aperture formed therein, for indicating characteristics of record matter on a card. 115

7. An index signal comprising a sheet having a plurality of tongues directed inwardly from the marginal portions thereof, said tongues being spaced from each other and said sheet by an opening formed by the removal of a section of the sheet adjacent the marginal portions and between said tongues, said tongues being formed for independent engagement on the marginal portion of a record card, each tongue providing a different signal element. 120

8. An index signal comprising a sheet having a plurality of tongues directed inwardly 125

from the marginal portions thereof in spaced relation, and signal means formed on each of said tongues each signal means being different from the other.

5 9. An index signal comprising a laminated sheet member, each lamination having a different color, and said member having inwardly directed tongues on the marginal portions thereof relatively spaced and each having a
10 different color on opposite sides thereof for independent signalling cooperation with a record card.

15 10. An index signal comprising a laminated sheet member having a plurality of tongues directed inwardly from the marginal portions thereof, said laminations being formed to provide independent signalling means on opposite sides of each tongue.

20 11. In combination, an index card, and a signal comprising a sheet member provided with a plurality of tongues directed inwardly from the marginal portions thereof, each of said tongues being independently engageable with a marginal portion of said index card
25 for signalling cooperation therewith, said card concealing the other tongues in non-signalling relation.
